UNITED STATES PATENT OFFICE.

FRED M. WOODS, OF FREEPORT, ILLINOIS, ASSIGNOR TO STOVER MANUFACTURING COMPANY, OF FREEPORT, ILLINOIS, A CORPORATION OF ILLINOIS.

COMMINUTING DEVICE.

1,190,499.

Specification of Letters Patent. Patented July 11, 1916.

Application filed October 14, 1915. Serial No. 55,828.

To all whom it may concern:

Be it known that I, FRED M. Woods, a citizen of the United States, residing at Freeport, in the county of Stephenson and State of Illinois, have invented certain new and useful Improvements in Comminuting Devices, of which the following is a specification, reference being had therein to the accompanying drawing.

10 The general object of this invention is to provide a machine which will with little waste of power rapidly reduce alfalfa and the like whether dry or otherwise to substantially uniform comminuted condition, 15 the degree of fineness being variable at will.

There has been much difficulty in providing a machine which will operate satisfactorily upon material in the widely different states just suggested, and this difficulty is 20 avoided in this machine largely by removing from the sphere of operation almost immediately all such material as has reached the desired degree of fineness, retaining the residue for further comminution, and doing this 25 by means which obviate clogging and material friction.

In the accompanying drawings, Figure 1 is a vertical section of the machine parallel to the general direction of the feed. Fig. 2 30 is an elevation, looking from the left in Fig. 1. Fig. 3 is a section on the line 3—3, Fig. 1.

In these figures, A represents a frame supporting the working parts of the machine, B a casing, of general cylindrical form, 35 closed above and having on one side an inlet passage B' and on the opposite side an outlet opening B² which like the passage B' extends approximately from end to end of the casing B. The cutting devices, which 40 are without novelty herein claimed, include rotary cutters co-acting with fixed knife bars. At the lower side of said inlet passage is fixed a knife bar C which projects into the casing to a line uniformly distant 45 from the axis thereof, and along the upper boundary of said outlet opening is fixed a second knife bar C' which projects inward to the same extent. A shaft D rotates in the axis of the casing and bears spiral cutters D' each having a cutting edge in position to co-act with the cutting edges of the two knife bars as the shaft rotates, but the arrangement being such that the shearing at the two lines is not simultaneous.

50 Material to be comminuted is brought by

a conveyer E and is crushed down and condensed thereon by rollers F, F'. After leaving the conveyer, the material passes between a roller G and a vertically movable co-acting roller G' and thence through the inlet passage B'. In advancing to the rollers last mentioned, the material is compressed between the rollers F', G' and a fixed inclined plate H which leads upwardly 60 from the conveyer and guides the mass to the horizontal plane passing between the rollers G, G', whereby the mass is compressed from below as well as from above, with some advantage, before it passes between the rollers G, G'. The cutter shaft 65 rotates at high speed and the entering mass of material is sheared by the rotary cutters in endless succession as they pass the first knife bar, all parts parallel to the line of advance being cut into short segments the 70 length of which depends upon the rate of feed and the speed of the cutter shaft. As the material is sheared at this cutter bar it moves downwardly forward in the annular 75 space of considerable radial width, surrounding the cutters and the finer portions escape, as will presently appear, while the coarser portion moves on in that space and is further sheared at the knife bar C', the 80 finer part and short segments thus removed largely falling between the cutters, although some small portion, including any long segments passes around to be sheared again with the entering material. The 85 result of this action is that there is constantly 90 in the space below the cutters a loose mass of coarse material from which fine material is constantly shaken by the action of the cutters, and from this mass countless successive small portions are rapidly sheared 95 at the knife bar C', so that there is never any clogging nor is the material ever so impacted as to cause material friction. In the opening B² a somewhat closely fitting 100 hollow perforated cylinder K is mounted to rotate about the axis of a shaft O parallel to the shaft of the cutters. The finer portion of the material in the casing constantly escapes into this cylinder and out of it again 105 at its lower side, the rate of discharge depending largely upon the speed of the cylinder's rotation, although cylinders having apertures of different sizes may be used interchangeably. Preferably the apertures in the cylinder are made with inwardly diver- 110

gent walls so that there may be less tendency of material to become fast in the openings. With this form of apertures the casting at the edge of the opening in which the cylinder lies removes any portions which may for the moment be caught in the holes.

With certain kinds of material, a simple perforated cylinder would operate satisfactorily, but in order that the same machine 10 may be used with material of any kind, the cylindrical shell is made up of stave-like sections L each pivoted near its forward edge to swing about an axis parallel to the cylinder's axis, the arrangement being such 15 that as the cylinder rotates the sections as they leave the opening B² are swung outward about the pivots L' opening the cylinder from end to end on its lower side. As they open they are in constant contact with 20 a fixed guide member M the inner surface of which progressively recedes from and as gradually returns to the cylindrical surface, so that the sections open noiselessly discharging any material in the cylinder and 25 then gently close before they again reach the opening B². The inward movement of the sections is limited in any convenient way, for example, by lugs P on the end portions of the cylinder, and they may be of 30 cast metal or may be made in any desired manner.

The fine material falling from the cylinder or from the devices at the end of the conveyer E is collected by hoppers O, O' 35 and then delivered as may be desired, usually to a conveyer or elevator.

It is well known that in machines of this general kind stems and stalks parallel to the shearing lines will not be cut into short 40 segments, and that the undivided portions often cause clogging or are delivered with the fine material. With the machine here set forth this evil is eliminated, and long pieces are never delivered and never clog the 45 machine, being quickly caught and divided after they are detached from the entering mass of material.

What I claim is:

1. In devices of the class described, the combination with comminuting devices, of a 50 lower roll having a fixed axis and a yielding roll co-acting with the first to deliver material to said devices, a conveyer for bringing material near said rolls, an inclined plate leading upwardly from said conveyer to the 55 upper side of the lower roll, and a yielding roll co-acting with the plate to raise the lower portion of the material and depress the upper portion, delivering the whole between said co-acting rolls. 60

2. In apparatus of the class described, the combination with a casing having a peripheral inlet passage and a peripheral discharge opening, of comminuting devices within the cylinder or casing, and a perforated cylinder rotating in said opening and permitting comminuted material to pass therefrom while barring the escape of coarser material. 65

3. In apparatus of the class described, the combination with a casing having a lateral discharge opening, of comminuting devices within the casing, a perforated cylinder fitting and rotating in said opening and provided with peripheral sections arranged to 70 remain closed when at said opening and to open when at the opposite part of their common path. 75

4. In apparatus of the class described, the combination with a casing having a lateral 80 discharge opening, of comminuting devices within the casing, a perforated cylinder fitting and rotating in said opening and provided with stave-like sections each pivoted to swing upon an axis parallel to the axis 85 of the cylinder and arranged to be closed when at said opening and to open when at a lower point in their common path.

In testimony whereof I affix my signature in presence of two witnesses.

FRED M. WOODS.
